UNITED STATES PATENT OFFICE.

HANS SCHMEISSER, OF SUHL, GERMANY.

SMALL ARM WITH TUBULAR CARTRIDGE MAGAZINE.

Application filed August 24, 1925. Serial No. 52,072.

To all whom it may concern:

Be it known that I, HANS SCHMEISSER, a citizen of Germany, residing at Philosophenweg 5, Suhl, Germany, have invented certain new and useful Improvements in Small Arms with Tubular Cartridge Magazines, of which the following is a specification.

My invention relates to improvements in small arms having a cartridge magazine formed in a known manner as a tube or sleeve located along the barrel. As the cartridges are moved out of the magazine singly by means of a spring enclosed within the tube or sleeve, they will be received 10 by and on the usual cartridge carrier acting to bring, when swinging upwards, the cartridge to a position right opposite or in front of the chamber.

The chief object of my invention is to 20 provide improved means for pushing the cartridge from the raised carrier into the chamber by means of a bi-partite breech-bolt having the one of its two parts dimensioned and arranged as to be capable of entering from the rear into the tubular front end of the cartridge carrier in which the lifted cartridge lies, in order to push the cartridge forward into the chamber of the barrel, and to be further adapted to disengage 25 from the tubular front end of the carrier upon the subsequent downward movement of the latter, while the other part of the breech-bolt will be retained in its rear position during the thus accomplished 30 charging operation and will not advance to also engage the bottom surface of the cartridge in the chamber, until the carrier has moved down and out of the path of the breech-bolt, to receive a next cartridge.

40 Preferably I construct the second mentioned part of the breech-bolt to constitute at the same time a firing pin or similar formation.

A further object of my invention is to 45 provide means for preventing the firing member which is combined, as hereinbefore stated, with the one part of the breech-bolt, from accidental firing of a shot. The said part of the breech-bolt is retained in cocked 50 position by means of a suitable pawl. By mounting the latter on the detachable cover of the breech casing on which also the bi-partite breech-bolt is mounted, accidental firing in case of removing the cover and if 55 the firing member is in cocked position and

a cartridge in the chamber, is efficiently prevented.

The invention further comprises a locking means on the detachable cover for retaining the two parts of the breech-bolt and preventing the same from being ejected from the casing by the action of the closing spring and the firing spring, in case of removing the cover from the casing. In 60 order to enable the cover to be readily removed from the casing, suitable ribs may be provided at the fore end and at the rear end thereof, adapted to engage in correspondingly shaped grooves provided in the wall of the casing. If desired another locking 65 means may be provided on the cover for the purpose of preventing the cover from accidentally removing from the casing or, in other words, holding the cover properly seated with its ribs in the said grooves of 70 the casing.

The invention further comprises a closing lever mounted on the right-hand side or on the left-hand side of the breech-bolt so as to be able to be moved or swung in a 75 vertical plane, a lateral recess or slot being provided in the casing or in the cover for receiving and guiding the lever which preferably is shaped to form a handle affording a ready means for causing the lever to engage in a suitable recess or with a projecting part of the casing or the cover, if required, so that the breech-bolt will be firmly locked and the weapon may be 80 used for firing single shots or repeated 85 shots.

The invention furthermore comprises the constructions and combinations of parts hereinafter particularly described and illustrated in the drawings.

90 In the accompanying drawings forming a part of this specification, and showing for purposes of exemplification, a preferred form and manner in which the invention 95 may be embodied and practised:

100 Figure 1 is a fragmentary vertical, longitudinal section of the weapon with a cartridge in the chamber, the parts being shown at the firing moment;

105 Figure 2 is a similar view of the middle part of the rifle with the breech-bolt fully withdrawn upon firing;

110 Figure 3 is a similar view of the weapon with the parts in the position of pushing a cartridge into the chamber;

Figure 4 is a front view of the cartridge carrier showing clearly the tubular front end thereof;

Figure 5 is a vertical longitudinal section of the cover or cover plate with the breech mechanism and the locking means mounted thereon, the parts being shown in their uncocked position;

Figure 6 is a similar view showing the parts in cocked position, the contour of the casing being indicated in Figures 5 and 6 in dotted lines;

Figure 7 is a vertical section taken on the line A—B in Figure 6;

Figure 8 is a vertical longitudinal section of the middle part of the rifle showing the casing viewed from the right-hand side with the closing lever in its inactive position;

Figure 9 is a similar view with the closing lever in its locking position;

Figure 10 is an elevation of the breech-bolt with the closing lever pivotally attached thereto;

Figure 11 is a plan view of the closing lever and

Figure 12 is a side view and a plan view of a detail.

Referring to Figures 1 to 3 the casing 1 is firmly connected with the barrel 2 and the tubular cartridge magazine 3 in the usual manner and the two parts 4 and 5 constituting the breech-bolt are mounted in the casing 1, as shown, subject to the action of the two coiled springs 6 and 7, respectively. At the front end of the part 4 of the breech-bolt a cartridge extractor 8 is pivotally mounted in the usual manner, whilst the front end or face of the part 5 of the breech-bolt is shaped to form a firing pin 5^a. When the parts 4 and 5 return from the closing position shown in Figure 1 to the open position illustrated in Figure 2, the part 5 is taken along with by a shoulder 4^c of the part 4.

The cartridge carrier 10 is mounted in the casing to swing about a transverse pin 9 or the like. The front end of the carrier is shaped to form a tubular seat 10^a for the reception of the cartridge to be transported from the magazine to the chamber. This tubular end of the carrier is recessed to be open at the top and at the rear, as shown at 10^b in Figures 1, 2 and 4, but the recess 10^b is only so wide that a cartridge cannot pass therethrough, whereas the part 4 of the breech-bolt can freely pass therethrough. The part 4 of the breech-bolt is provided with two lugs projecting downward from the bottom side thereof, the one lug 4^b being at the rear end of the part 4 and the other one, 4^a, being located at a point intermediate between the two ends of the part 4. When the latter moves backward towards the butt, the lug 4^a will engage the short arm 10^c of the cartridge car-

rier and cause the longer arm of the carrier to rise and to thereby bring a cartridge into a position in front of the chamber, as shown in Figure 2, and when the part 4 moves forwards towards the barrel, the lug 4^b will engage the arm 10^c of the carrier 10 and cause the longer arm thereof to descend from the position illustrated in Figure 2 to that shown in Figure 1.

Pivotaly mounted on a pin 12 in the casing is a pawl 13 which will lock the part 5 of the breech-bolt, when in the full open or rear position, by catching into a notch 5^b provided for the purpose in the bottom face of the rear end of the part 5. As hereinbefore stated the front arm of the carrier 10 is raised by the action of the lug 4^a when the breech-bolt moves backward or towards the butt, so that the tubular end 10^a of the arm will bring a cartridge from the magazine to the chamber of the barrel 2, see Figure 2. When subsequently the part 4 of the breech-bolt is moved in opposite direction or towards the barrel, the said part 4 will pass from the rear end through the recess 10^b into the tubular seat 10^a of the carrier and push the cartridge out of the seat 10^a into the chamber of the barrel, as will be clearly seen upon inspection of Figure 3. At the very moment the cartridge has come out of contact with the carrier the lug 4^b of the part 4 will engage the short arm 10^c of the carrier and cause the latter to turn about its pivot 9 thereby lowering the front arm of the carrier into the position illustrated in Figure 1, so that the tubular fore end 10^a of the arm will be in readiness for the reception of a new cartridge from the magazine. At the same time the part 5 of the breech-bolt has been caught by the pawl 13 engaging in the notch 5^b and is locked until, upon firing, the pawl 13 is moved to release the part 5 which then is rapidly thrown forward by the action of the compressed spring 7 in order to cover that portion of the bottom face of the cartridge in the chamber which is not covered or in contact with the fore end of the part 4 of the breech-bolt, and to cause at the same time the firing pin 5^a to hit the cartridge in the chamber.

Referring to Figures 5 to 7, 1 denotes the stationary casing. The barrel and the cartridge magazine are not shown in Figures 5 to 7, but they are of usual constructions and arrangement as hereinbefore stated with reference to Figures 1 to 4. The bipartite breech-bolt comprising a closing member or part 4 and a firing member or part 5, as before, is mounted on the cover or cover plate 1^a so as to be capable of moving backward and forward. The cartridge extractor 8 is provided, as before, in the fore end of the part 4. The locking pawl 13 pivoted on a pin 12 se-

cured in the cover 1^a, is actuated by a spring 13^a causing the pawl to catch into the notch 5^b of the part 5 and to lock the latter in the position shown in Figure 6, 5 when the breech bolt is moved into its extreme hind position.

In the fore-end of the cover 1^a and on the inner side or face thereof a T-shaped groove is provided for the reception of a 10 locking latch 15 shaped to correspond to the shape of the groove so as to be slidable therein. The groove and the latch are located transverse to the length of the cover and a spring 15^a normally holds the latch 15 in a raised position so that its upper end lies in the path of the breech-bolt whereby the two parts of the latter are prevented from being ejected over or out of the front end of the cover if the latter is to be removed from the casing. 20

Further the fore end and the rear end of the cover are equipped with ribs 1^b adapted to engage in correspondingly shaped grooves of the casing 1. Furthermore a horizontal bore is provided in the rear end of the cover to accommodate a latch-bolt 14 having a lateral knurled head 14^b. The rear or free end of the bolt 14 normally lies in a recess 14^a of the casing 30 under the action of a spring 14^c abutting against the fore end of the bolt, as will be clearly seen in Figures 5 and 6 whilst Figure 7 shows the parts in section.

Referring to Figures 8 to 12 showing 35 the casing 1 viewed from the other side, the sliding breech-bolt 4 is located either in the casing 1 or on the cover 1^a and a coiled spring 6 is provided for moving the same into the closed position, that is towards the barrel not shown. The longitudinal slot 1^e is enlarged and shaped to afford a locking face 1^d lying in an arc of a circle the centre of which is in the pivot of the breech lever 16. When the latter is turned downward the arm 16^e will engage behind the face or shoulder 1^d so that the breech-bolt will be locked.

For the purpose of yieldingly securing 50 the lever 16 in its two limits or end positions I utilize the main spring 6. To this end I provide in the rear end of the lever 17 two notches 16^a and 16^b and I mount onto the free end of the coiled spring 6^a a firing bolt 17, shown separately in Figure 12 and having a tooth 17^a adapted to catch, under the pressure of the spring 6, either into the notch 16^a or into the notch 16^b, depending upon the position of the lever 16, so that the latter will be resiliently fixed in either position. The bolt 17 has a vertical bore 17^b of elongated or elliptical cross-section and I provide a vertical pin 18 passing through the bore 17^b in order to guide the bolt 17 in vertical 65 direction.

I have not attempted to explain all of the details of the construction of the rifle, for it will be understood by those to whom this specification is addressed, that those parts of the rifle which are not shown and described will necessarily be of the usual construction and relationship and will be properly mounted and supported according to the tenets of small-arm construction. 70

It seems unnecessary to reiterate the operation of the rifle, for the operation of the improved parts has been described in detail and the operation of the parts which are old and not shown is known to persons skilled in the art. Nor does it seem necessary to burden this specification with an exposition of the advantages which the invention possesses, for they will be apparent to those versed in the art to which this invention relates. 75

It is also apparent that in carrying out my invention some changes from the construction herein shown and described may be made. I would, therefore, have it understood that I do not limit myself thereto, but hold myself at liberty to make such departures therefrom as fairly fall within the spirit and scope of my invention. 80

What I claim is:—

1. A repeating rifle of the type described comprising a casing; a cover having a groove; a breech bolt in said cover having a closing member and a firing member; a spring-pressed locking pawl pivoted in said cover adapted to hold the firing member in cocked position; a locking latch adapted to slide in said groove; and means in the cover adapted to engage in the casing. 95

2. A repeating rifle of the type set forth, comprising a barrel, a tubular cartridge magazine below the said barrel, a two-part breech-bolt, a casing enclosing the breech and cooperating parts, a cover on top of the said casing, a locking lever holding the one part of the breech-bolt in cocked position, a spring-controlled locking latch for preventing the latter from being ejected when the cover is to be removed from the casing, and a spring-controlled latch-bolt for securing the said cover in its position on the said casing, the said breech-bolt, the lever, the locking latch and the latch-bolt being mounted on the said removable cover, substantially as and for the purpose set forth. 105

3. A repeating rifle of the type set forth, comprising a barrel, a tubular cartridge magazine below the latter, a cartridge carrier adapted to swing in a vertical plane, a breech-bolt, a casing enclosing said breech-bolt, a coiled spring actuating the breech-bolt, a cover to shut up the said casing, a rotary closing or breech-lever mounted laterally on the said breech-bolt, a longitudinal slot with a shoulder in the said casing for guiding and arresting the said 110 120 125 130

- 4 lever, and a means co-operating with the said spring to secure the said lever in its locking position, substantially as and for the purpose set forth.
- 5 4. A repeating rifle of the type described comprising a casing; a cover having a groove; a breech bolt in said cover having a closing member and a firing member; a spring-pressed locking pawl pivoted in said cover adapted to hold the firing member in 10 cocked position; a locking latch adapted to slide in said groove; and ribs in the cover adapted to engage in correspondingly shaped grooves in the casing.

In testimony whereof I affix my signature.

HANS SCHMEISSER.
